ELECTRIC CAN OPENER

Frank J. Hart, Fairlawn, N.J., assignor to Jay Kay Metal Specialties Corporation, Long Island City, N.Y., a corporation of New York

Filed Oct. 14, 1960, Ser. No. 62,495

Term of patent 7 years

(Cl. D22—2)

FIG. 1

FIG. 2

FIG. 1 is a front perspective view of an electric can opener, showing my new design.

FIG. 2 is a top plan view thereof.

FIG. 3 is a side elevational view thereof.

FIG. 4 is a front elevational view thereof.

I claim:

The ornamental design for an electric can opener, substantially as shown.
